UNITED STATES PATENT OFFICE.

EDMOND FLORIMOND LEVAIRE, OF PARIS, FRANCE.

RAIL-JOINT.

1,396,272.

Specification of Letters Patent.

Patented Nov. 8, 1921.

Application filed December 9, 1919. Serial No. 343,648.

(GRANTED UNDER THE PROVISIONS OF THE ACT OF MARCH 3, 1921, 41 STAT. L., 1313.)

To all whom it may concern:

Be it known that I, EDMOND FLORIMOND LEVAIRE, citizen of the Republic of France, residing at 4 Rue Jouffroy, Paris, in the Republic of France, have invented new and useful Improvements in Rail-Joints, for which I have filed an application in France, Dec. 7, 1918, Patent No. 493,917, of which the following is a specification.

10 This invention relates to improved means for fishing rails and comprises essentially the combination of two fish-plates which are forcibly driven into the space between the under surface of the rail head, the upper surface of the rail flange and a backing or supporting surface formed either by the free surface of securing keys or wedges, or an adjacent surface of claws which are provided on metal sole-plates or on the sleepers 15 themselves. Said backing surface may be either plane, inclined with respect to the longitudinal direction of the rail, at right angles to the under face of the rail flange or inclined upwardly toward the head of the 20 rail. The said keys may also be formed integrally with the corresponding fish-plate.

The main advantages of the improved rail joint are as follows: It is exceedingly strong. Holes in the rails and fish-plates are dispensed with whereby the risks of fracture are reduced. Fishing may be readily effected between rail lengths or broken parts at any point of the length of the rail whatever kind of joint is used (butt joint, skew 35 joint, or scarf-joint). The use of coach-screws and fish-bolts is avoided. The cost of manufacture and maintenance of the track and fish-plates is reduced. Moreover, the detrimental effects which take place at 40 the joint are carried over to a supported member *i. e.* the sole-plate or sleeper. The safety in the traffic is increased. All pairs of fish-plates are exactly alike when using a single type of metal sleeper adapted for use 45 with different track-gages. If the sleepers are of a single type, all the fish-plates are exactly alike.

In the annexed drawings:—

Figures 1, 2, 3, 4 and 5 show by way of 50 example one embodiment of rail joint in accordance with the invention, the lower half of Fig. 1 below the center line X—X¹ being a plan view and the upper half a hori-

zontal section along the line Y—Y¹ of Fig. 3, the keys being omitted in the upper half 55 section and the rail being cut horizontally in its web part.

Fig. 2 is a side view of Fig. 1.

Fig. 3 is a vertical section along the line 3—3 of Fig. 1.

Fig. 4 is a perspective view of one of the keys.

Fig. 5 is a perspective view of one end of a fish-plate.

Fig. 6 is a sectional elevation showing 65 another embodiment in which the fish-plate bears upon the key by a flat face at right angles to the rail flange.

Each sleeper T is provided with two claws T', one at each side of the rail R. The 70 rail is held in place by means of two lateral keys or wedges C C' which are forcibly driven into the space between each claw and the upper face of the rail flange.

As shown in Figs. 1 to 4, the two adjacent 75 sections of the rail are fished to each other by means of two fish-plates E—E' forming strut or prop members for the rail and provided at each end, on the outer face thereof, with a lateral projection E². Each lateral projection has its lower outer edge removed so as to form an angular bearing surface which tapers in the longitudinal direction. One end edge of said bearing surface is indicated by the line 3—4 in Fig. 3, 85 the opposite end edge being indicated by the line 1—2.

Each fish-plate is driven endwise into position in the same direction as the keys C C', as shown by the arrows, into the space 90 between the under surface 7—8 of the rail head, the upper face 5—6 of rail flange and the tapering longitudinal free surface of the corresponding key or wedge C or C'. By referring to Fig. 4, it will be seen that each 95 key such as C' comprises two longitudinal portions tapering in opposite directions, the surface of the portion engaging with the projection on the fish-plate being shown at 11, 22, 33, 44. This taper is for instance 100 about 25 millimeters per meter.

It will be understood that the portion 11, 22, 33, 44 of the surface of the key may vary in width and may be at all of its points higher than the under face of the claw. 105 Said part 11, 22, 33, 44 may have in cross

section the form of a right, an acute or an obtuse angle, a fillet being provided at the edge as shown. The fish-plates may be shaped in cross section as shown in the drawing. The radius in cross section of the cut away part 1, 2, 3, 4, of the fish-plate may be somewhat smaller than that of the corresponding surface 11, 22, 33, 44 of the key.

When each fish-plate has been forcibly 10 driven and seated in place, *i. e.* in its working position, it is locked in the longitudinal direction so as to prevent any possible loosening by means of a wire F having a square cross section, which engages in a longitudinal 15 groove r of each fish-plate projection E^2 and is held at one end by having its extremity bent at right angles and engaged into a hole t provided in the projection E^2 near the middle of its length, its other end being 20 bent against the end face of the key as shown in Fig. 1.

By means of the above described arrangement and the shape of the fish-plates, the fish-plates are held upon the rails with a 25 heavy pressure which opposes any displacement of the fish-plates either in the longitudinal direction or laterally off the rails. The fish-plates as well as the keys may be solid or hollowed. They may be made of 30 cast-pressed steel or rolled steel or of any other material having a sufficient strength. The face 6-7 may be more or less concave or it may be a plane face at right angles to the base of the rail flange.

35 The device above described for locking the fish-plate in the longitudinal direction may be replaced by any other suitable device and it may be also entirely dispensed with. As a matter of course, the wire may be replaced 40 by a flat metal band or by a bar having any other suitable profile.

It will be understood that the bearing surface 1, 2, 3, 4 of the fish-plate projection may be either plane, inclined to the longitudinal 45 direction of the rail, and at right angles to the rail flange or inclined toward the head of the rail and situated at the middle of the height of the fish-plate.

Fig. 6 shows a modification comprising a 50 fish-plate E^3 provided with a bearing surface $1^a, 2^a, 3^a, 4^a$ formed on a projection E^4 on the fish-plate. Said projection has the shape of a triangular prism at right angles to the flange of the rail, the bearing surface 55 being a plane surface inclined upwardly in the longitudinal direction of the rail. C^a is the corresponding key. Said bearing surface $1^a, 2^a, 3^a, 4^a$ instead of being formed on a projecting part of the fish-plate, may obviously be formed by the wall of a recess in 60 the side face of said fish-plate.

Having now described my invention, what I claim as new and desire to secure by Letters Patent is:

65 1. A rail joint comprising the combina-

tion of supporting members adapted to support the rail sections, respectively, two lateral opposite claws integral with each supporting member each claw comprising a substantially horizontal projecting or beak portion and a body portion, four tapering keys adapted to be forcibly driven all in the same direction each in contact with one claw on the supporting members, respectively, and two fish-plates provided with wedge surfaces and adapted to be forcibly driven all in the same direction as the keys, the fish-plates bearing under the head and upon the flange of the rail sections on the one hand and against the other members of the joint 80 on the other hand.

2. A rail joint comprising the combination of supporting members adapted to support the rail sections, respectively, two lateral opposite claws integral with each supporting member each claw comprising a substantially horizontal projecting or beak portion and a body portion, four tapering keys adapted to be forcibly driven all in the same direction each in contact with one claw 90 on the supporting members, respectively, and two fish-plates provided with wedge surfaces and adapted to be forcibly driven all in the same direction as the keys, the fish plates bearing under the head and upon the 95 flange of the rail sections on the one hand and against the keys respectively.

3. A rail joint comprising the combination of supporting members adapted to support the rail sections, respectively, two lateral opposite claws integral with each supporting member, each claw comprising a substantially horizontal projecting or beak portion and a body portion, four tapering keys adapted to be forcibly driven all in the 100 same direction each in contact with one claw on the supporting members, respectively, and two fish plates provided with projecting wedge surfaces and adapted to be forcibly driven all in the same direction as the keys, the fish plates bearing under the head and upon the flange of the rail on the one hand and the keys on the other hand, respectively.

4. A rail joint comprising the combination of supporting members adapted to support the rail sections, respectively, two lateral opposite claws integral with each supporting member each claw comprising a substantially horizontal projecting or beak portion and a body portion, four tapering keys 115 adapted to be forcibly driven all in the same direction each in contact with one claw on the supporting members, respectively, and two fish plates provided with projecting wedge surfaces and adapted to be forcibly driven all in the same direction as the keys, the fish plates bearing under the head and upon the flange of the rail on the one hand and the keys on the other hand, respectively. 120

5. A rail joint comprising the combination of supporting members adapted to support the rail sections, respectively, two lateral opposite claws integral with each supporting member each claw comprising a substantially horizontal projecting or beak portion and a body portion, four tapering keys 125 adapted to be forcibly driven all in the same direction each in contact with one claw on the supporting members, respectively, and two fish plates provided with projecting wedge surfaces and adapted to be forcibly driven all in the same direction as the keys, the fish plates bearing under the head and upon the flange of the rail on the one hand and the keys on the other hand, respectively, and locking members for the fish plates, in- 130

- serted in grooves formed in the fish plates, one end of said locking members extending into a recess in the fish plate and the opposite end being bent around the end face of 5 another member of the joint, respectively.
5. A rail joint comprising the combination of supporting members adapted to support the rail sections, respectively, two lateral opposite claws integral with each sup- 10 porting member each claw comprising a sub- stantially horizontal projecting or beak portion and a body portion, four tapering keys adapted to be forcibly driven all in the same direction each in contact with one claw on 15 the supporting members, respectively, and two fish plates provided with projecting sur- faces comprising a lateral recess or rabbet having a vertical wall and a horizontal wall connected to the vertical wall by a small 20 fillet, said vertical and horizontal walls forming wedge surfaces, the fish plates being adapted to be forcibly driven all in the same direction as the keys, the fish plates bearing under the head and upon the flange of the 25 rail on the one hand and the said wedge sur-
- faces engaging at the same time with the keys on the other hand.
6. A rail joint comprising the combination of supporting members adapted to support the rail sections, respectively, two lat- 30 eral opposite claws integral with each sup- porting member and comprising a substan- tially horizontal projecting or beak portion and a body portion, two pairs of tapering keys on either side of the rail sections re- 35 spectively, the two keys in each pair being forcibly driven in the same direction in contact each with one claw, respectively, and two fish-plates one on each side of the rail sections, respectively, said fish-plates being 40 provided with wedge surfaces and bearing under the head and upon the flange of the rail sections on the one hand and against the other members of the joint on the other hand, each of them being forcibly driven in 45 the same direction as the two corresponding keys.

In testimony whereof I have signed my name to this specification.

EDMOND FLORIMOND LEVAIRE.
